United States Patent Office

Des. 193,041
Patented June 12, 1962

193,041

BOAT

Ray E. Leger, Paramount, Calif., assignor to The Power
Cat Boat Corporation, a corporation of California

Filed June 22, 1960, Ser. No. 61,067

Term of patent 14 years

(Cl. D71—1)

FIG. 1.

FIG. 2.

FIG. 3.

FIG. 4.

FIG. 5.

FIGURE 1 is a top plan view of a boat illustrating my new design;

FIGURE 2 is an elevational view of a side thereof;

FIGURE 3 is a front elevational view thereof;

FIGURE 4 is a bottom plan view thereof; and,

FIGURE 5 is a rear elevational view thereof.

The characteristic features of my boat design reside in the portions thereof which are located above the chines.

I claim:

The ornamental design for a boat, substantially as shown and described.
